UNITED STATES PATENT OFFICE.

JOE GIBSON, OF HOUSTON, TEXAS.

MAIL-STATION DEVICE.

Specification of Letters Patent.

Patented Dec. 21, 1915.

1,165,242.

Application filed December 19, 1914. Serial No. 878,116.

To all whom it may concern:

Be it known that I, JOE GIBSON, a citizen of the United States, residing at Houston, in the county of Harris and State of Texas, have invented new and useful Improvements in Mail-Station Devices, of which the following is a specification.

The invention relates to a mail box, and more particularly to the class of rural mail station devices.

The primary object of the invention is the provision of a device of this character wherein mail matter may be placed so that all outgoing mail can be collected in a convenient manner, while each person in a determined territory can receive the incoming mail, thereby obviating the necessity of a rural carrier for the delivery of the mail from box to box throughout a given route.

Another object of the invention is the provision of a mail station device wherein the mail matter for each person in a determined area is held in individual receptacles, the same being accessible only to the person possessing the key to the lock thereof, while all of said receptacles are accessible to a mail carrier for the distribution of the incoming mail matter therein, thus in this manner the wrong acquisition of mail matter deposited in the device will be obviated, it being impossible to procure the mail for one person by another unless the individual receptacle therefor is tampered with, which would disclose a malicious act on the part of such person.

A further object of the invention is the provision of a station device of this character wherein the individual receptacle can be shifted therein to bring the same in position so that access may be had thereto by the user of such receptacle so that the mail placed therein by the collector can be taken therefrom, the device being of novel form and obviating the necessity of the rural free delivery equipment ordinarily used.

A still further object of the invention is the provision of a device of this character which is extremely simple in construction, reliable and efficient in operation, strong, durable, and inexpensive in manufacture.

With these and other objects in view, the invention consists in the construction, com-

bination and arrangement of parts as will be hereinafter fully described, illustrated in the accompanying drawings, and pointed out in the claims hereunto appended.

In the drawings:—Figure 1 is a front elevation of a device constructed in accordance with the invention. Fig. 2 is a rear elevation thereof. Fig. 3 is a vertical longitudinal sectional view taken on the line 3—3 of Fig. 1. Fig. 4 is a vertical transverse sectional view. Fig. 5 is a sectional view on the line 5—5 of Fig. 1, showing the slide door open and locking the wheel-like drum stationary.

Similar reference characters indicate corresponding parts throughout the several views in the drawings.

Referring to the drawings in detail, the device comprises a casing 5, preferably made from galvanized sheet metal, although it may be made from any other suitable material, and has a rounded top 6, the front wall of the casing being formed with a circular opening 7 and a slot 8, through the latter of which is inserted outgoing mail matter, which is caught within a hopper or cage 9 located within the casing 5 and mounted on the inner face of the front wall in any suitable manner.

Arranged above and below the circular opening 7 in the front wall of the casing 5 on the inner face of the said front wall are guideways 10 in which is slidably mounted a gate or door 11 provided with a transparent central peep opening 12 and a finger knob 13 which projects through the opening 7 beyond the front wall of the casing so that the gate or door 11 can be opened or closed at will.

The casing 5 is open at its rear and has hinged to opposite sides thereof swinging door sections 14 which are adapted to close the opening in the rear or back of the said casing. Fixed within the lower end of the casing 5 is a rectangular shaped reinforcing frame 15 to which the walls of the casing are secured, and extending from this frame to the rounded top 6 of the casing at the rear thereof is a central brace strip 16 which carries a staple 17 fixed therein in any suitable manner and is adapted to pass through slots 18 formed in the door sections 14 so that a lock 19 can be engaged with

this staple 17 for the fastening of the doors in closed position. The key of the lock 19 is adapted to be in the possession of the mail carrier so that the door sections 14 can be 5 only opened by the mail carrier for the distribution of incoming mail within a mail receiver mechanism interiorly of the casing 5 so that the mail deposited can be acquired 10 by a determined number of persons within 10 a given area or territory in a manner presently described.

Arranged within the casing 5 in the upper portion thereof is a rotatable sprocket-wheel-like operating drum 20 which is fixed 15 upon an axle or shaft 21 journaled in a bearing 22 secured to the brace 16 and in the front wall of the casing 5, the end journaled in the front wall of the casing being extended and carries a cross handle 23 so 20 that the drum 20 can be turned without the casing. Trained over the drum 20 is an endless chain-like series of individual receptacles 24, each being formed at diametrically opposite points near opposite ends 25 thereof with ears 25 through which are passed pivots 26 connecting the receptacles 24 in chain-like fashion so that they will travel over the drum 20 on the rotation thereof, the opening 7 in the wall of the 30 casing 5 being arranged so that each receptacle 24 will register therewith on actuating the drum, and into these receptacles is adapted to be placed mail matter by the mail carrier, to be subsequently taken therefrom 35 by the person using the receptacle. The receptacles 24 at their rear ends are formed with openings 27 through which is placed mail matter by the mail carrier when the door sections 14 have been opened at the 40 rear of the casing. Now, on closing the door sections 14 at the rear of the casing 5 it will be impossible to gain access to any or all of the receptacles 24 through the openings 27 in the rear thereof.

45 The front ends of the receptacles 24 are open, and are adapted to be closed by means of doors 28 which are hinged thereto in any suitable manner, each door being provided with a lock 29, the locks on the doors of the 50 respective receptacles 24 being controlled by individual keys distinctive with respect to each other so that the possessor of the key for opening one of the receptacles 24 cannot gain access to another receptacle, thereby 55 insuring the users of the receptacles 24 from the wrongful acquisition of mail matter from the receptacles by unscrupulous or malicious persons.

60 The series of mail receptacles 24 are provided with numerals ranging consecutively at the front and rear ends of the receptacles throughout the series thereof so that the user and mail carrier can determine at a glance the intended receptacle for such user

so that the mail matter can be properly distributed and acquired by the respective users of the series of receptacles within the casing 5 of the device. The numerals at the front ends of the receptacles 24 are clearly visible through the peep opening in the door 11 when closing the opening 7 in the front wall of the casing.

The rotatable sprocket-like operating drum is formed on its front side concentrically about the axle or shaft 21 with radial 75 ribs or wings 30, with any one of which is adapted to engage a lug 31 on the gate or door 11 when moved to open position so as to lock the drum against rotation for holding any one of the receptacles 24 in alignment with the opening 7 in the front of the casing so as to enable free access to be had thereto for the placing of mail matter therein or the removal of mail matter therefrom.

From the foregoing it is thought that the construction and manner of operation of the device will be clearly understood, and therefore a more extended explanation has been omitted.

What is claimed is:—

1. A mail station device comprising a casing having an opening in its front, a series of individual mail receptacles connected to each other and movable within the 95 casing for successive registration with the opening in the front thereof, doors mounted at the front of the receptacles and having individual locks, means for moving the receptacles without the casing, a door closing 100 the opening in the front of the casing and having a peep opening, and indicia provided at the front and rear ends of the respective receptacles and consecutively arranged.

2. A mail station device comprising a 105 casing having an opening in its front, a series of individual mail receptacles connected to each other and movable within the casing for successive registration with the opening in the front thereof, doors mounted at the front of the receptacles and having individual locks, means for moving the receptacles without the casing, a door closing the opening in the front of the casing and having a peep opening, indicia provided 110 at the front and rear ends of the respective receptacles and consecutively arranged, and means at the rear of the casing for permitting access to all of the receptacles.

3. A mail station device comprising a 120 casing having an opening in its front, a series of individual mail receptacles connected to each other and movable within the casing for successive registration with the opening in the front thereof, doors mounted 125 at the front of the receptacles and having individual locks, means for moving the receptacles without the casing, a door closing

the opening in the front of the casing and having a peep opening, indicia provided at the front and rear ends of the respective receptacles and consecutively arranged, means at the rear of the casing for permitting access to all of the receptacles, the said casing being provided in its front with a slot, and a receiving cage mounted within the casing

for communication therewith through the slot.

In testimony whereof I affix my signature in presence of two witnesses.

JOE GIBSON.
